GOTTFRIED WIRRER, OF PLAINFIELD, NEW JERSEY, AND ARLINGTON CLINTON MOYER, OF ALLENTEW, PENNSYLVANIA, ASSIGNEES TO INTERNATIONAL MOTOR COMPANY, OF NEW YORK, N. Y., A CORPORATION OF DELAWARE.

SCLEROSCOPE.

Application filed March 29, 1921. Serial No. 456,688.

To all whom it may concern:

Be it known that we, GOTTFRIED WIRRER, a citizen of the Swiss Republic, and ARLINGTON CLINTON MOYER, a citizen of the United States, residing, respectively, in Plainfield, in the State of New Jersey, and in Allentown, in the State of Pennsylvania have invented certain new and useful Improvements in Scleroscopes, of which the following is 10 a specification, reference being had to the accompanying drawing, forming a part hereof.

This invention relates to an improved scleroscope, that is, a machine for testing 15 the hardness of materials and particularly of metals.

Machines of the same general character with which the present improvements are concerned have been devised and employed 20 with some degree of success in scientific laboratories for some time. Such machines, however, generally have relied upon rather complicated operating devices for the testing hammer which have been actuated by pneumatic means. The result has been a very 25 complicated, delicate and expensive machine, lacking somewhat in the desired degree of accuracy and by no means unvariable in its readings, degrees of error being consequently introduced by reason of the very 30 nature of the control devices employed. The present invention has for its general object to improve machines for the purpose described by substituting for the complicated 35 and uncertain pneumatic control devices heretofore employed a positive mechanical release for the hammer of a very simple and inexpensive character. The control devices now proposed being of a positive mechanical nature insure the instant release of 40 the hammer with unvarying certainty under corresponding conditions, thereby eliminating one source of error characteristic of pneumatically operated devices.

Another source of error which has been 45 present in scleroscopes as known has been the pressure vacuum set up by the falling hammer within its indicating tube. By the present improvements it is assured that the 50 hammer shall always fall freely in a normal atmosphere and be subject to equal pressures on its two sides.

Another unsatisfactory feature of known scleroscopes has been that the pneumatic de-

vices for actuating the control for the hammer have necessitated several reciprocations of the suction piston during a single test. The present scleroscope is so constructed that one reading of the hammer can be taken during each reciprocation of the controlling element, the hammer being automatically returned to position for a further reading each time.

Reference is now to be had to the accompanying drawing for a detailed description 65 of one simple embodiment of the improvements, in which drawing—

Figure 1 is a view in vertical section of a fragment of the improved scleroscope showing particularly the control devices for 70 the falling hammer.

Figure 2 is a view in elevation of a complete machine showing the relation of parts and the indicating scale for readings.

Scleroscopes test the hardness of materials 75 by affording the observer an opportunity to read the extent of rebound of a hardened hammer when permitted to fall a predetermined distance on to the material to be tested. To obtain accurate readings it is 80 evident that the control devices for releasing the hammer and all of the associated parts should be of such character as to bring about a fall under unvarying conditions so that the relative heights of rebound can be noted 85 by the observer. As shown in Figure 2 the machine comprises generally a base *a* on which is supported a vertical transparent tube *b*, graduated in equal divisions, as indicated at *c*. The material to be tested is 90 indicated at *d*, and is placed under the lower open end of the tube *b* to afford a striking base for a hardened hammer *e* which is permitted to drop from the top of the tube on to the material, its rebound within the tube 95 as noted from the scale readings indicating a certain degree of hardness of the material tested, as compared with other materials, the hardness of which can be tested in the same manner. The present improvements 100 relate particularly to the control devices for effecting the reading, positive and unvariable release of the hammer *e* and permitting it to fall within the tube in the normal atmosphere and with equal pressures on its 105 two sides. The hammer *e* is shown as recessed at *e'* and flanged at *e''* to receive opposed hooks *f* pivoted as at *f'* in the head *f''* of

the machine. These hooks while supporting the hammer *e* in raised position are actuated to release the hammer for its fall. The upwardly extending arms of the hooks *f* terminate in cam edges *f*³ adapted to bear against the inner wall of a hollow steel cone *g*. By pressing down on this steel cone *g* it will be evident that the lower ends of the hooks *f* will be brought together for the release of the hammer *e*. The cone *g* is normally held in raised position by means of a spring *g*'. The upper edge of the ring *g* is engaged by a plunger *h* mounted to reciprocate in a cylinder *i* secured to the head *f*² of the machine. Within the opening in the ring *g* and extended upwardly into the plunger *h* is a tumbler *k* having a conical recess in its lower end against which bear the curved ends of the hooks *f*. The action of the tumbler *k* on the hooks is to force their lower ends apart so as to hold them in engagement with the retaining flange *e*² on the hammer *e*. The plunger *h* is recessed, as indicated, to receive the end of the tumbler *k* and also a spring *k*' which constantly presses the tumbler downwardly but yieldingly into engagement with the upper end of the hooks *f*. The upper end of the plunger *h* terminates in a stem *h*' which extends through a central opening *i*' formed in the upper wall of the cylinder *i*. The stem *h*' may carry on its end a bearing roller *h*². The plunger *h* may have its end finished off with a washer *h*³ which constitutes a seat and closes off the interior of the cylinder *i* against the opening *i*'.

The upper end of the stem *h*' with the roller *h*² rests within an upper cylinder *l* which is secured removably on the lower cylinder *i* by means of bolts *l*'. The bore of the cylinder *l* has mounted to reciprocate therein a piston *m* carrying a stem *m*' which extends through the end wall *l*² of the cylinder *l* and may have at its extreme end a convenient finger button *m*² to facilitate manual operation. Interposed between the end wall *l*² of the cylinder *l* and the button *m*² is placed, in the illustrated embodiment, a spiral spring *n* for holding the piston *m* yieldingly at the upper end of the cylinder *l*. The interior of the cylinder *l* is open to the atmosphere through an aperture *l*³ formed conveniently in the end wall *l*², so that reciprocations of the piston *m* within the cylinder take place at normal atmospheric pressure. The interior of the cylinder *l* is preferably in communication with the interior of the cylinder *i* through registering channels *l*⁴, *i*³, formed respectively in the walls of said cylinders.

The operation of the machine is positive and insures the release of the hammer *e* under varying conditions. With the hammer in raised position and supported by engagement of the ends of the hooks *f* with

the retaining flange *e*² and with the material *d*, whose hardness is to be tested, under the lower open end of the tube *b*, the improved devices provide for the convenient and sharp release of the hammer so that its rebound can be observed. The lower ends of the hooks *f* are held in engagement with the flange *e*² by the pressure exerted on the upper ends of the hooks by the spring-pressed tumbler *k*. At this time the spring *g*' acting on the ring *g* will seat the plunger *h* through its gasket *h*³ on the upper end of the cylinder *i*. The operator presses the piston *m* downwardly in the cylinder *l* against the action of the spring *n* by pressure on the stem *m*'. As soon as the piston *m* overruns the end of the channel *l*⁴, atmospheric pressure in the upper end of the cylinder *l* will be permitted to the interior of the cylinder *i* and to the interior of the tube *b* through the channel *i*³. Continued movement of the piston *m* will bring it in engagement with the roller *h*² and force the plunger *h* downwardly so as to slide the conical ring *g* along the cam surfaces *f*³ on the opposed forks so as to press the lower ends thereof together and disengage them from the supporting flange *e*² for the hammer *e*. The release of the hammer is thus effected by positive mechanical devices. The cam will be released quickly and will fall in the tube *b* in a normal atmosphere. Its drop cannot, as in previous devices, result in the creation of a pressure vacuum behind it so as to retard its free drop under gravity. The rebound of the hammer *e* after striking the material *d* will be observed from the scale *c*. After taking the reading, the operator will release the pressure on the stem *m*' as to permit the spring *n* to move the piston *m* upwardly in the cylinder *l*. As soon as the piston *m* overruns the end of the channel *l*⁴ its continued movement will create suction within the tube *b* sufficient to draw the hammer *e* from the lower end thereof up into engagement with the hooks *f*. The hooks will be locked as before by the spring-pressed tumbler *k*. By the operation described it will be evident that upon one complete reciprocation of the piston *m* a reading will have been secured and the hammer will have been returned to position in readiness for another reading. This simplicity of design and operation is important and marks an improvement of known devices in which several operations were necessary to release the hammer and then return it to raised position for a further reading.

It will be desirable to limit the downward movement of the piston *m* while in engagement with the end of the stem *h*' since its continued movement might result in undue movement of the ring *g* and excessive spreading of the forks *f* to a point where

they might be injured. Such means for limiting the downward movement of the piston *m* is provided in an adjustable stop screw *o* which can be threaded in the lower 5 cylinder *i* and have its end *o'* exposed within the cylinder *l* and in such relation to the roller *h*² and the piston *m* as to arrest the movement of the latter after predetermined movement of the stem *h'*.

10 The striking characteristics of the improved machine are simplicity of construction, directness and certainty of operation and unvariable conditions of release of the hammer. With these broad objects in mind, 15 it will be understood that the devices are not to be limited to the structural details shown and described herein since a skilled mechanician can, as to each of the elements, substitute equivalents therefor or change their 20 details according to circumstances without modifying the modus operandi of the machine.

We claim as our invention:

1. In a machine for testing the hardness 25 of materials, a hammer, an open ended tube in which the hammer moves, devices for supporting the hammer releasably in raised position in said tube including a hook engageable with the hammer, a cylinder carried on the tube and communicating therewith through an air port, a manually operable piston reciprocable in the cylinder and means engageable by the piston and with the hook for moving the latter out of 35 engagement with the hammer, said piston being adapted to overrun said air port before release of the hammer to place the tube in communication with the atmosphere.

2. In a machine for testing the hardness 40 of materials, a hammer, an open ended tube in which the hammer moves, devices for supporting the hammer releasably in raised position in said tube including a hook engageable with the hammer, a cylinder carried on the tube and communicating therewith through an air port, a manually operable piston reciprocable in the cylinder and means engageable by the piston and with the hook for moving the latter out of 45 engagement with the hammer, said piston being adapted to overrun said air port before release of the hammer to place the tube in communication with the atmosphere, and 50 said piston in its return movement being 55 adapted to overrun said port and draw the

hammer up into engagement with the retaining hook by creating suction within the tube.

3. In a machine for testing the hardness 60 of materials, a hammer, an open ended tube in which the hammer moves, hooks for supporting the hammer releasably in raised position, a cylinder supported on the tube, a plunger mounted reciprocably within the cylinder and co-operating with means for 65 swinging the hooks to release the hammer, a second cylinder mounted on said first cylinder but in communication therewith through communicating channels, a stem on the plunger extending through the end wall 70 of the first named cylinder into the second named cylinder, a piston mounted reciprocably within the second named cylinder and having a stem for manual operation of the piston, said piston being subjected on its 75 rear side to atmospheric pressure and adapted to overrun the said channels to place the tube in communication with the atmosphere before engaging the stem of the plunger for release of the hooks. 80

4. In a machine for testing the hardness 85 of materials, a hammer, an open ended tube in which the hammer moves, hooks for supporting the hammer releasably in raised position, a cylinder supported on the tube, a plunger mounted reciprocably within the cylinder and co-operating with means for 90 swinging the hooks to release the hammer, a second cylinder mounted on said first cylinder but in communication therewith through communicating channels, a stem on the plunger extending through the end wall of the first named cylinder into the second named cylinder, a piston mounted reciprocably within the second named cylinder and having a stem for manual operation of the piston, said piston being subjected on its 95 rear side to atmospheric pressure and adapted to overrun the said channels to place the tube in communication with the atmosphere before engaging the stem of the plunger for 100 release of the hooks, and an adjustable stop mounted within the second named cylinder to limit the movement of the piston after engagement with the stem. 105

This specification signed this 30th day of September, A. D. 1921.
